THOMAS HILL, OF FORT WAYNE, INDIANA.

DESIGN FOR AN ORGAN-CASE.

Design No. 19,915, dated June 17, 1890.

UNITED STATES PATENT OFFICE.

THOMAS HILL, OF FORT WAYNE, INDIANA.

DESIGN FOR AN ORGAN-CASE.

SPECIFICATION forming part of Design No. 19,915, dated June 17, 1890.

Application filed April 9, 1890. Serial No. 347,276. Term of patent 7 years.

To all whom it may concern:

Be it known that I, THOMAS HILL, a citizen of the United States, residing at Fort Wayne, in the county of Allen and State of Indiana, ⁵ have invented a new and original Design for an Organ-Case, of which the following is a specification, reference being had to the accompanying photographs, forming part thereof.

Figure 1 is a front view of an organ-case ¹⁰ showing my design, and Fig. 2 a perspective view of the same.

One of the principal features of my design consists in what is commonly called a "roll-cover" ¹⁵ A for the key-board C and a small one B for the music-rest, which is located just above the key-board. Upon opposite sides of the music-holder rise a series of shelves D, resting upon corner-posts E, and ²⁰ surmounted by the ornamental cornices F.

An ornamental top G connects these two tiers

of shelves and forms between them an alcove H, in which is located an ornamental shelf I. The effect of this arrangement is to produce a casing of great beauty and attractiveness.

Having thus described my design, what I ²⁵ claim is—

The design for organ-cases herein described and shown, the same comprising a roll-cover for the key-board, a roll-cover for the music-holder, and tiers of shelves supported by corner-posts, said shelves being located upon opposite sides of the music-holder, substantially as described and shown. ³⁰

In testimony whereof I affix my signature in presence of two witnesses.

THOMAS HILL.
